COATING MACHINE

James I. Tickelis, Haverhill, Mass., assignor to
Bestco Shoe Machinery Inc., Ipswich, Mass., a
corporation of Massachusetts

Application February 7, 1938, Serial No. 189,104

4 Claims. (Cl. 12—80)

The present invention consists in an improved machine for applying a liquid coating to an article or a portion thereof, a machine which is useful for a variety of purposes but which is particularly adapted for applying a band of cement upon the over-lasted margins of lasted shoes in that process of manufacture wherein soles are secured to uppers by pyroxalin or other cement.

One object of my invention is to provide a liquid coating machine wherein the liquid reservoir is substantially sealed from air in order to prevent excess evaporation and make possible the use of relatively volatile liquids as coating material. Furthermore, by preventing excess evaporation, coagulation and increased viscosity may be minimized.

A further object of my invention is to provide a liquid coating machine wherein the parts are so located as to afford the operator an unobstructed view of the work being coated, particularly at the point of application. To this end an important feature of the invention consists in an applicator roll arranged to project from the machine at an angle to present an inclined liquid carrying surface.

An important feature of my invention resides in a screw conveyor disposed within the reservoir and arranged to deliver a constant supply of liquid to the innermost portion of the applicator roll, in combination with a gauge for regulating the amount of liquid delivered outside the reservoir by the applicator roll.

Another feature of my invention resides in a novel gate used for sealing the reservoir when the applicator roll is removed, so that the machine may be left between intervals of use without undue loss of liquid from the reservoir or objectionable hardening thereof on exposed parts.

These and other objects and features of my invention will be best understood and appreciated from the following description of preferred embodiments thereof, selected for purposes of illustration and shown in the accompanying drawings, in which

Fig. 1 is a view in side elevation and partly in section of a liquid coating machine embodying my invention,

Fig. 2 is a view in perspective of the applicator roll and gauge therefor,

Fig. 3 is a view in perspective showing the gate in position, and

Fig. 4 is a view in side elevation showing details of the gauge.

My invention may be briefly described as a liquid coating machine consisting of a reservoir

for liquid, an applicator roll arranged for rotation partially within the reservoir, a screw conveyor disposed in the reservoir and arranged to discharge a predetermined, constant amount of liquid upon the innermost surface of the applicator. A sliding gauge is mounted adjacent the applicator, and manipulation thereof varies the thickness of the band of liquid carried upon the periphery of the applicator roll. To prevent hardening of viscous liquids on the applicator roll the latter may be removed for cleaning when the machine is not in operation.

Referring first to Fig. 1, it will be apparent that the body of the machine is supported on a box-like base 10 provided with an orifice into which projects a horizontal shaft 12 driven from a motor 11 and carrying a worm 13.

Projecting above the base 10 are bearings 15 and 16 which support a horizontal shaft 14 with its ends projecting freely beyond the bearings. 20 Keyed to the shaft 14 between the bearings 15 and 16 is a worm wheel 17 in mesh with the worm 13. On the free ends of the shaft 14 are keyed bevel gears 19 and 20. Integral with the bearing 15 is a bearing 22 which supports a forwardly inclined applicator shaft 24 to the lower end of which is secured a bevel gear 26 in constant mesh with the gear 19.

The upper portion of the machine is inclosed in a casing having a wall 28 extending upwardly 30 and forwardly from the top of the base 10 and terminating at its upper end in a bearing 32. The casing incloses a reservoir 30 spaced above the base 10 and having a forwardly and upwardly inclined bottom. The reservoir 30 is provided 35 with a hinged cover 34 which constitutes the forward portion of the reservoir inclosure. A headed screw 36 in the cover 34 may be screwed into the side wall of the reservoir 30 to maintain the cover 34 in closed position.

Secured to the upper end of the applicator shaft 24 is an applicator roll which comprises a central metal hub 39, having an integral lower flange and a removable upper flange, and an outer concentric roll 38 of hard corrugated rubber. The upper flange of the hub 39 is provided with a centrally located depression in which bears a cone point screw 40. The cone point screw 40 is threaded in the cover 34 and may be adjusted and locked in position by a check nut 40. 45 As the gear 19 turns, it tends to force the gear 26 and the applicator shaft 24 upward. The bearing 40 resists this upward thrust, being held down by the set screw 36.

Journalized in the bottom of the reservoir is an 55

inclined conveyor shaft 43 provided with an integral spiral flange or feather 44, thus forming a screw conveyor. The lower end of the shaft 43 extends below the reservoir 30 and carries a 5 bevel gear 45 which is in constant mesh with the gear 20 on the driven shaft 14. A tubular metal casing 46 of circular cross section surrounds the shaft 43 and the flange 44 and is provided with a stud 48 which seats in a recess in a 10 large lug extending upwardly from the bottom of the reservoir 30. A set screw 49 is threaded into the lug 47 and bears against the stud 48, thereby supporting the casing 26 in fixed position. The casing 46 terminates adjacent the 15 innermost upper surface of the applicator roll 38.

The reservoir 30 is provided with a filling cover 51 and a drain plug 52. A curved cover plate 54 is screwed to the rear of the base 10 and the 20 reservoir 30 to prevent dust and dirt from reaching the gears and bearings. Reference character 53 designates the presence of liquid in the reservoir 30.

A gauge is shown in Figs. 2 and 4 in conjunction with the applicator roll 38. A rectangular block 56 is mounted to slide transversely in the upper end of the inclined wall 28 and is provided with a vertical groove in its inner face into which fits a collar 59 integral with an adjusting screw 30 57 threaded into the wall of the reservoir 30. The adjusting screw 57 has a knurled head 58 to facilitate manual adjustment. As the adjusting screw 57 is moved in and out, the block 56 is carried with it. A hard rubber piece 60 is secured to the inner end of the block 56 by a screw 62 (see Fig. 4) passing through a hole in the block 56 and an elongated slot 61 in the rubber piece 60. The latter is notched at its inner end to fit over the periphery of the applicator roll 40 38. An elongated gate 63 is adapted to fit into a slot on the end of the applicator shaft 24, when the applicator roll has been removed therefrom, and to fill completely the opening in the casing formerly occupied by the applicator roll. A 45 notch is cut in the upper edge of the gate 73 to accommodate the cone point bearing 40.

The operation of the machine when used for upper cementing will now be described. The reservoir 30 is filled with a liquid cement having 50 a volatile solvent. When the overlasted margins of shoe uppers are to be coated with cement, a pyroxalin cement is used in the reservoir. The motor is then started, whereupon the shaft 14 is caused to rotate through the worm 13 and the 55 worm wheel 17. Consequently the applicator 38 is caused to rotate through the gears 26 and 19, and gears 20 and 45 operate the screw conveyor 44 which carries cement continuously to the upper end of the casing 46 and dumps a constant 60 supply thereof on the innermost portion of the applicator roll 38. Excess cement drips from the applicator roll back into the main body of cement in the reservoir 30. The applicator roll 38 rotates past the end of the casing 46 and carries 65 with it a band of cement. The gauge piece 60 is withdrawn from the surface of the roll 38 a distance equal to the thickness of the band of cement which it is desired to apply to the overlasted margin of the upper. Any excess cement is held back by the gauge 60 and finds its way 70 back to the main body of cement in the reservoir 30. Thus, the thickness of the cement to be applied may be regulated by varying the position 75 of the gauge piece 60 by the bolt 57.

The operator of the machine holds a shoe so that the overlasted margin of the upper is in contact with the outermost surface of the roll 38. The shoe is then advanced and turned so that a band of cement is applied to the entire 5 surface of the overlasted margin of the upper. The fact that the applicator roll 38 juts out from the body of the machine is advantageous, since the operator is thereby enabled to watch the coating operation clearly and perform accurate 10 work. When a relatively thick band of cement is to be applied, the adjusting screw 57 is retracted, thus increasing the distance between the gauge 60 and the roll 38 to allow more cement to pass through. When the machine is 15 not in operation, the applicator roll is removed from the shaft 24 and placed in a can of solvent or other cleaning fluid. Otherwise cement would harden on the roll and prevent subsequent operation of the machine. To seal the reservoir 20 from the atmosphere, the gate 63 is placed in position and the cover 34 is secured in closed position by the set screw 36 with the cone point of the screw 40 fitting in the notch and holding the gate firmly in position with the gauge 60 25 enclosed behind it.

While the operation of the machine has been described in connection with cementing a shoe upper, it is obvious that my machine may be used for any operation wherein it is necessary 30 to apply a band of cement or other liquid material to the surface of an article. The conveying mechanism is entirely disposed within the reservoir, and the applicator roll is partially disposed therein. By preventing a supply of excess 35 air to the reservoir I have reduced the rate of evaporation and made possible the use of coating liquids containing relatively volatile constituents. Coagulation of adhesive liquids is avoided and the machine will not gum up, if properly 40 cared for.

Having thus described my invention, what I claim as new and desire to secure by Letters Patent of the United States is:

1. A liquid coating machine comprising a 45 shaft, bevel gears on each end of said shaft, an applicator shaft geared to one of said bevel gears, a screw conveyor geared to the other bevel gear, an applicator roll carried on said applicator shaft adjacent one end of said screw conveyor, a liquid 50 reservoir encompassing said screw conveyor and a portion of said applicator roll, an adjustable gauge block adjacent said applicator roll, a hinged cover on said reservoir, and a cone point bearing threaded into said cover for engaging 55 the applicator roll.

2. An upper cementing machine comprising a base, a shaft journaled on said base with its ends free, bevel gears on either end of said shaft, a forwardly inclined applicator shaft geared to one 60 of said bevel gears, an applicator roll keyed on the upper end of said applicator shaft, a cement reservoir disposed above said base, an inclined screw conveyor disposed in said reservoir and geared to one of the bevel gears on said shaft, 65 said screw conveyor being arranged to discharge cement constantly upon the innermost surface of said applicator roll.

3. A liquid coating machine including a reservoir having a wall with an opening for an applicator roll, bounded in part by a hinged cover plate, an applicator roll shaft terminating below the opening and having a slot in its end, and a gate shaped to fill the opening in the reservoir, to fit into the slot of said shaft and to be re- 70 75 80 85 90 95 98 99 100

tained in position by engagement of the cover plate.

4. A liquid coating machine comprising a base supporting a reservoir and having a driven shaft journaled beneath the same, an upwardly inclined shaft geared to one end of the driven shaft

and carrying an applicator roll at its upper end, and an upwardly inclined conveyor shaft converging toward the applicator roll shaft, geared to the other end of said driven shaft and located within the reservoir.
